UNITED STATES PATENT OFFICE

172,660

FOLDING CHAIR

Steve G. Budai, Cincinnati, Ohio, assignor to Balcrank, Inc., Cincinnati, Ohio, a corporation of Ohio

Application October 29, 1953, Serial No. 27,385

Term of patent 14 years

(Cl. D15—8)

To all whom it may concern:

Be it known that I, Steve G. Budai, a citizen of the United States, residing at Cincinnati, in the county of Hamilton and State of Ohio, have invented a new, original, and ornamental Design for a Folding Chair, of which the following is a specification, reference being had to the accompanying drawing, forming a part thereof.

The figure is a perspective view of a folding chair showing my new design.

I claim:

The ornamental design for a folding chair, substantially as shown.
